SOUND PRODUCING DEVICE

Wilhelm Hanf, Vierheim, near Mannheim, Germany, assignor to Rheinische Gummi- und Celluloid-Fabrik, Mannheim-Neckarau, Germany

Application August 7, 1956, Serial No. 602,540

6 Claims. (Cl. 46—184)

The present invention relates to a sound-producing device for a doll or the like, and more particularly to a voice device, or "mama-voice" as this type of unit is generally called in the trade.

Voice devices according to the prior art are not suitable for use in dolls or other toys which are to be immersed in water because entry of water into the device interferes with the proper functioning thereof.

It is an object of the present invention to provide a waterproof voice device.

It is a further object of the present invention to provide an inexpensive device for rendering voice devices waterproof so that they may be used in toys which are to be immersed in or otherwise brought into contact with water or other fluids.

Another object of the present invention is to provide a waterproof structure which is easily and cheaply applied to well-known types of voice devices.

Yet another object of the present invention is to provide a waterproof voice device which is of sturdy plastic material and which can be assembled in a simple, yet effective manner.

It is another object of the present invention to provide a waterproof voice unit for dolls which can be used in courses which are designed to instruct in the methods of bathing and handling infants.

Yet another object of the present invention is to provide a voice device which is protected from entry thereof into water, dust and other materials whereby impairment of the functioning of the voice device is avoided.

With the above objects in view, the present invention mainly consists in a waterproof device for a voice box comprising a membrane of vibratable waterproof material mounted on the box and means fastening the membrane to the voice box in such a manner that functioning of the voice box is not impaired while at the same time entry of water into the voice box is prevented.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a sectional view illustrating one embodiment of the invention;

Fig. 2 is a sectional view illustrating another embodiment of the invention;

Fig. 3 is a fragmentary enlarged sectional view of the encircled portion of Fig. 1; and

Fig. 4 is a fragmentary enlarged sectional view of the encircled portion of Fig. 2.

Referring now to the drawings, Fig. 1 and Fig. 3 show the invention illustrated with one of the various voice devices available on the market. The sound device, illustrated schematically in the drawing, is a well-known "mama-voice" which comprises a cylindrical container

2

10 having an opening 11. Perforated closure plate member *e* extends in opening 11 of the container. Slidably arranged within the container is the weight 12 to which the bellows 14 formed from collapsible fluid-tight material, for instance, impregnated fabric, is connected. Centrally mounted on the plate member *e* is a valve member 16 which cooperates with a central bore in the weight member 12 and a vibrating reed (not shown in the drawing) in well-known manner, to produce a crying sound during the downward movement of the weight from its top position in which the upper surface of the weight contacts the bottom surface of the plate member *e* to the position shown in the drawing.

The sound waves produced by the voice described will pass through the apertures of the plate member *e* and set the membrane *d* in vibration so that the sound produced by the voice inside the container 10 will be transmitted through the vibrations of the membrane *d* to the outside thereof.

20 Although the present embodiment is described with reference to the type of voice box illustrated herein, it is understood that other types of voice or any other sound-producing mechanism might be used as well.

As shown in Fig. 3, a plastic waterproof vibratable membrane *d* is tautly fitted and fixed over the opening of the container spaced from the closure plate member *e*, by means of clamping members *a* and *b*. The edge portions of the membrane are held between the clamping members *a* and *b* and mounted on the container upper portion *c*. The clamping members are preferably annular rings of plastic material. Adhesive material is preferably used to cement the ring *b* to the container. The rings may be fixed to the membrane, also, by an adhesive substance.

30 Further, the rings may be of the type which seal the container by tightly fitting on to the container portion *c* with the edge portions of the membrane clamped tightly between the members so as to provide a fluid-tight seal without using adhesive material.

35 In Figs. 2 and 4 there is shown another embodiment of the invention in which the container 20 is preferably made of injection-molded plastic material and may have inner shoulder means 22 on upper portion *c* on which the closure plate member *e* can be seated and fixed. The clamping or fastening means shown in Fig. 4 has only one ring *a*¹ which is clamped on to the container over the edges of the membrane and which interfits with outer shoulder means 24 of the container. The inner portion of the container above shoulder 22 serves to space the membrane *d* from the closure plate member *e*.

40 As with the embodiment of Figs. 1 and 3, the embodiment according to Figs. 2 and 4 may have the fluid-tight seal formed with the aid of an adhesive substance or cement which can be placed between ring *a*¹ and container portion *c* at shoulder 24. Sealing material may also be placed between the container and the membrane and between the membrane and the adjacent portion of ring *a*¹ to provide a secure fluid-tight arrangement to protect the sound producing mechanism in the container.

45 Either or both clamping members may be of plastic material and the container of a conventional voice box may be sprayed with a waterproofing material or otherwise coated to render it impervious to water.

50 It is noted that the membrane *d* is disposed in the embodiments of the invention in such a manner that it can vibrate freely within the cavity between the body of a doll and the plate member *e* so that functioning of the voice box is not impaired while at the same time the mechanism is protected from water damage.

55 70 The container is shown herein as being of cylindrical shape and having an open end. The clamping or fasten-

ing means are shown as annular. However, variations of shape are well within the scope of the invention.

A container of any other shape having an opening may be provided with sound-producing means other than those described and illustrated herein. The waterproofing membrane covering the open end may be spaced in the manner described and illustrated herein or by means of additional spacing members. The clamping means may be annular members as set forth herein or there may be provided some other type of fastening means to hold the membrane mounted on the container in such a manner as to avoid impairment of the functioning of the sound-producing means.

It will be understood that each of the elements described above, or two or more together, may also find a useful application in other types of sound-producing device differing from the types described above.

While the invention has been described as embodied in a waterproof voice device for a doll, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of the prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A water-proof doll voice comprising, in combination, a voice box having an open end; a sound producing device located in said voice box; a closure plate extending transversely across the interior of said voice box in the region of the open end thereof and being formed with a plurality of apertures therethrough permitting passage of sound waves emanating from said sound producing device through said closure plate; a water-proof membrane extending substantially parallel to said closure plate over the same; and annular clamping means at said open end of said voice box fluid-tightly and non-shiftably clamping said membrane on said voice box in a position spaced from said closure plate at a sufficient distance so that said membrane may swing freely without engaging said closure plate whenever sound waves emit through said apertures, whereby said membrane will prevent entrance of water into said voice box while transmitting the sound waves emanating therefrom.

2. A water-proof doll voice comprising, in combination, a voice box having an open end; a sound producing device located in said voice box; a closure plate extending transversely across the interior of said voice box in the region of the open end thereof and being formed with a plurality of apertures therethrough permitting passage of sound waves emanating from said sound producing device through said closure plate; a water-proof membrane extending substantially parallel to said closure plate over the same; and annular clamping means at said open end of said voice box fluid-tightly and non-shiftably clamping said membrane on said voice box in a position spaced from said closure plate at a sufficient distance so that said membrane may swing freely without engaging said closure plate whenever sound waves emit through said apertures, said annular clamping means having a free rim portion extending in axial direction of said voice box beyond said membrane, whereby said membrane will prevent entrance of water into said voice box while transmitting the sound waves emanating therefrom.

3. A water-proof doll voice comprising, in combination, a voice box having an open end; a sound producing

device located in said voice box; a closure plate extending transversely across the interior of said voice box in the region of the open end thereof and being formed with a plurality of apertures therethrough permitting passage of sound waves emanating from said sound producing device through said closure plates; a water-proof membrane extending substantially parallel to said closure plate over the same; and annular clamping means at said open end of said voice box fluid-tightly and non-shiftably clamping said membrane on said voice box in a position spaced from said closure plate at a sufficient distance so that said membrane may swing freely without engaging said closure plate whenever sound waves emit through said apertures, said annular clamping means including an inner annular member of water-proof material fluid-tightly engaging the outer periphery of said voice box and having a free rim portion extending beyond the open end of said voice box, and an outer annular member of water-proof material located about said inner annular member so as to form a narrow annular gap between said two members in which the periphery of said membrane is fluid-tightly clamped and said outer annular member having a free rim portion extending in axial direction beyond the free rim portion of said inner annular member, whereby said membrane will prevent entrance of water into said voice box while transmitting the sound waves emanating therefrom.

4. A water-proof doll voice comprising, in combination, a voice box having an open end defined by an annular end face; a sound producing device located in said voice box; a closure plate extending transversely across the interior of said voice box adjacent the open end thereof inwardly spaced from said annular end face and being formed with a plurality of apertures therethrough permitting passage of sound waves emanating from said sound producing device through said closure plate; a water-proof membrane extending substantially parallel to said closure plate over the same; and annular clamping means at said open end of said voice box fluid-tightly and non-shiftably clamping said membrane on said voice box in a position spaced from said closure plate at a sufficient distance so that said membrane may swing freely without engaging said closure plate whenever sound waves emit through said apertures, whereby said membrane will prevent entrance of water into said voice box while transmitting the sound waves emanating therefrom.

5. A water-proof doll voice comprising, in combination, a voice box having an open end defined by an annular end face; a sound producing device located in said voice box; a closure plate extending transversely across the interior of said voice box adjacent the open end thereof inwardly spaced from said annular end face and being formed with a plurality of apertures therethrough permitting passage of sound waves emanating from said sound producing device through said closure plate; a water-proof membrane extending substantially parallel to said closure plate over the same; and annular clamping means at said open end of said voice box fluid-tightly and non-shiftably clamping said membrane on said voice box in a position spaced from said closure plate at a sufficient distance so that said membrane may swing freely without engaging said closure plate whenever sound waves emit through said apertures, said annular clamping means including an annular member located about the outer periphery of said voice box adjacent said open end thereof and fluid-tightly clamping said membrane against the outer periphery of said voice box, said annular member having a free rim portion extending beyond said membrane, whereby said membrane will prevent entrance of water into said voice box while transmitting the sound waves emanating therefrom.

6. A water-proof doll voice comprising, in combination, a voice box having a closed and an open end; a sound producing device mounted in said voice box for sliding movement from said closed toward said open end

and back; stop means on said voice box for limiting the sliding movement of said sound producing device toward said open end in a predetermined position within said voice box and spaced from said open end thereof; and a water-proof membrane extending over said open end of said voice box spaced from said predetermined position of said sound producing device, said membrane being non-shiftably and fluid-tightly fastened to said voice box, so that said membrane may swing freely in any position of said sound producing device so as to transmit 10 the sound waves emanating therefrom.
